Primary Examiner — Jennifer L Watkins(57) CLAIM

The ornamental design for jacket, as shown and described.

DESCRIPTION

The file of this patent contains at least one drawing/photograph executed in color. Copies of this patent with color drawing(s)/photograph(s) will be provided by the Office upon request and payment of the necessary fee.

1. Jacket

1.1 : Front

1.2 : Back

1.3 : Left

1.4 : Right

1.5 : Top

1.6 : Bottom

1.7 : Enlarged

1.8 : Enlarged

The parts shown in yellow color are not part of the claimed design; 1.1: front; 1.2: back; 1.3: left; 1.4: right; 1.5: top; 1.6: bottom; 1.7: enlarged view of the design shown in fig. 1.1; 1.8: another enlarged view of the design shown in fig. 1.1.

1 Claim, 8 Drawing Sheets
